UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

ORE CAR.

Application filed July 21, 1922. Serial No. 576,526.

Figure 1 is a plan view of my improved ore car.

Figure 2 is a side elevational view partly in vertical section of said car.

5 Figure 3 is an end elevational view.

Figure 4 is a partial vertical sectional view through the center of the car.

Figure 5 is an end elevational view of one end of the car.

10 Figure 6 is a fragmentary plan view of one corner of the car.

This invention relates to a new and useful improvement in ore cars, the object being to construct a car of the character described 15 so that it will be cheap, strong and durable in service.

20 My improved ore car contemplates the utilization of a cast steel underframe which forms the subject-matter of the companion application Serial No. 576,527, filed by me of even date herewith, which underframe readily adapts itself to the peculiar superstructure, doors, hopper doors and door operating mechanism illustrated in the accompanying drawings.

25 Various features of novelty reside in the arrangement and combinations of the several parts herein described and afterward pointed out in the claims.

30 In the drawings, the underframe is shown as a steel casting having horizontally disposed webs 7 at each end constituting end platforms, these webs being lightened by suitable openings and being provided with 35 finishing faces upon which are secured knee braces 25 constituting mounts for a part of the door operating mechanism. These braces also support and brace the end floor sheets of car.

40 26 indicates body corner posts in the form of angles which are secured to the corners of the underframe. 27 indicates body side posts and 32 indicates body end posts extending upwardly parallel to the posts 26, these 45 posts being bridged at points intermediate their ends by rods 28 constituting ladders. The upper ends of these posts are secured to a corner connection 29 to which is attached a connecting plate 30, (see Figure 6), this

50 plate being provided with hand-hole openings, 30^a, for well understood purposes. The outer edges of this plate are provided with clearance recesses which permit the necessary hand clearance about top ladder members. By this construction, all of the ladder

members of each group can be placed in substantially the same vertical plane, and side rods 28 are substantially flush with the sides of the car and end rods 28 do not project beyond the striking plate or dead block D 60 projecting from the end sill and it is possible to arrange the topmost rung of the ladder within four inches of the top of the car, as contemplated by safety regulations. This construction permits utilization of the full 65 lateral dimension for capacity of inside of car instead of having the ladders limit this capacity.

32^a indicates intermediate end posts secured by suitable connection plates 33 to the 70 horizontal webs 7 of the underframe. 34 indicates the end hopper wall curved, as shown in Figures 1, 2, and 6, said wall being connected at its lower edge by suitable rivets to the inclined hopper wall 8 formed integral 75 with the underframe. The brace angle 35 serves to support the middle portion of the end wall 34. The side edges of this end wall are connected to a side wall 36, the lower end of which side wall is bent inwardly as 80 at 37 to form a side sheet whose lower edge is riveted to inclined ledge 17 of the underframe (see Figure 4).

38 indicates a knee brace secured to finished faces 16 along the side sill for supporting the side hopper sheet portion 37. The upper ends of the side walls 36 are cut on an incline, as at 36^a so that they may be riveted to the side edges of the curved end upper walls, this construction avoiding corners and 90 angles in which the lading may lodge. The upper edges of the side and end walls of my improved car are preferably reinforced by means of bulb angles 40, (see Figure 4), which angles connect at their ends with top 95 end reinforcement angles 41, which latter assume the shape of the upper edges of the curved end walls 34; the horizontal flanges of the angles 40 and 41, being connected or spliced by the plate 30, at the corners of the car, heretofore referred to. Plate 30 has a handhole 30^a opposite the ladder so that it may be grasped by the brakeman in ascending or descending.

100 The side walls 36 are braced by connected angles 42 (see Figure 2), and the side sheets, which are preferably made in two pieces, are spliced by the plate 43 (see Figures 1 and 2).

105 The doors 44, see Figures 3 and 4, are 110

preferably made of cast steel having hinge lugs which cooperate with pintles passing through the lugs 8^d on the underframe, said lugs 8^d being located under the lading shed

5 17. The wall 45 is a baffle plate attached to underframe to guide ore into the proper place when unloading. Being made of cast steel, the doors may be reinforced by longitudinally disposed ribs 46 and transversely 10 disposed ribs 47 on their undersides, and by a longitudinal bolster which carries the load between extensions 48, thus preventing distortion of the door due to lading being dropped on it. These doors are further described and claimed in my copending application, Serial No. 600,336, now Patent 1,450,615, issued September 3, 1923. Each door at its swinging edge is provided with an extension 48 forming part of the casting 15 to which is connected the door operating mechanism, the latter forming no part of my present invention.

In Figures 1 and 2, I have shown a type 20 of truck peculiarly adapted to hopper bottom ore cars of this class, said truck being similar to that disclosed in the patent to Pflager, No. 995,560, dated June 20th, 1911. In this type of truck, the truck side frames, indicated at 50, are pivotally connected at 25 A to the bearing plates 21 of the cast steel underframe and consequently when taking a curve and the truck side frames swing from the position shown at the left in Figure 1 to the position shown exaggerated at 30 the right in said figure. Such pivoting of the truck side frames moves their inner ends away from the hopper portion of the underframe which extends downwardly below the tops of the truck.

40 By this construction, the car is "short-coupled" in having a comparatively narrow wheel base requiring a minimum clearance movement of the truck parts relative to the underframe and its connected parts. I, 45 therefore, prefer to use this type of truck in connection with my improved ore car instead of a swiveling truck such as is commonly employed, because when the parts of the swiveling truck move in taking a curve, their radius is such that a sufficient amount of clearance must be provided between the truck parts and the underframe parts so as to accommodate the movement of the truck 50 in taking the small curves of the shortest radius. In other words, the parts of the swiveling truck will move toward the hopper or the door operating mechanism when the car is taking a curve, whereas with the 55 type of truck shown, the parts of the truck may move away from the hopper.

60 What I claim is:

1. In a railway car, a cast steel underframe including integral webs inclined from 65 the vertical and curved horizontally and providing a hopper opening between them, and

curved sheets secured to said webs and extending upwardly therefrom to form hopper walls.

2. In a railway car, the combination of a cast steel underframe having integral walls 70 forming a centrally arranged hopper opening, the end walls of which are obliquely disposed and curved, and curved end hopper sheets whose lower edges are connected to the upper edges of the curved obliquely disposed walls on said underframe. 75

3. In a railway car, a cast steel underframe comprising integral longitudinal sills and transverse sills including inclined webs which extend from the top of the underframe downwardly beyond the bottoms of 80 said sills to form the lower portions of hopper walls, and superstructure sheets extending upwardly from said webs to complete the hopper walls. 85

4. In a railway car, an underframe including spaced longitudinal sills converging at their ends, a truck including a side frame pivoted intermediate its ends to the converging portions of said sills, and a hopper wall 90 extending downwardly below the top of said side frame and adjacent to but beyond the inner end of the latter.

5. In a railway car, the combination of a cast steel underframe having integral end walls forming a hopper opening, the end walls of which opening are inclined and curved, end hopper sheets inclined and curved and connected to said end walls, corner posts, top reinforcing members on the upper edges of said end hopper sheets and connection plates secured to said posts and 95 said members. 100

6. In a railway car, the combination of a cast steel underframe having walls forming a hopper opening, end and side hopper sheets secured to the edges of said walls, knee braces, corner posts, and side posts adjacent to said corner posts, said posts providing supports for ladder members, and 105 ladder members attached to said posts. 110

7. In a railway car, an underframe, a hopper body, body corner posts, body posts spaced from said corner posts, hopper vertical side sheets terminating short of said latter-mentioned posts, ladder rungs secured to said posts with their hand gripped portions substantially flush with the said side sheets, the upper one of said ladder rungs 115 being located adjacent to the top edge of the hopper body. 120

8. In a railway car, the combination of an underframe and hopper sheets, of corner posts, side posts adjacent to said corner posts, ladder member secured to said posts, and top corner connection plates, said plates being provided with hand openings opposite said ladder members. 125

9. In a railway car, the combination of an underframe having a centrally located 130

- hopper and sills converging at the ends of the hopper opening, downwardly opening doors for closing said hopper, and hopper parts extending below the horizontal plane 5 of certain of the truck parts, and truck parts including side frames pivoted on said sills, wheels and axles, the inner extremities of said parts being adjacent to said hopper walls and nearest said hopper when the truck 10 is in its normal position.
10. In a railway car, the combination of an underframe having a centrally located hopper and sills converging at the ends of the hopper opening, doors for closing said 15 hopper, centrally arranged operating mechanism for said doors, and truck parts including truck side frames, wheels and axles, said truck side frames being pivotally connected to said sills at four points spaced from the 20 longitudinal center line of the car whereby when the car is on a straight track the inner wheels and truck parts will be near the hopper and when the car is on a curved track the inner wheels and truck parts will move 25 away from the hopper.
11. In a railway car, an underframe, a hopper body having a vertical side portion, body corner posts, body posts spaced from said corner posts, ladder rungs secured to 30 said posts and located beyond the end of and substantially flush with said side portion of said hopper body, the upper one of said ladder rungs being located adjacent to the top edge of the hopper and lying in substantially the same vertical plane as other 35 ladder rungs in the same ladder.
12. In a hopper car, the combination of an underframe including a dead block, superstructure corner posts, end posts located between said corner posts, a hopper end sheet, the middle upper portion of which is located between said end posts and is nearer to the end of the car than the side portions 40 between said end posts and corner posts, and ladder members secured to said corner and end posts inside of the vertical plane of the front of said dead block, the upper one
- of said ladder members being adjacent to the level of the top edge of said end sheet and in substantially the same vertical plane 50 as other ladder members in the same group.
13. In a railway car, the combination of an underframe and hopper sheets, of corner posts, end and side posts adjacent to said corner posts, ladder members secured to said posts and top corner connection plates, said plates being provided with clearance recesses adjacent to top ladder members. 55
14. In a railway car, the combination of an underframe and hopper sheets, of corner posts, end and side posts adjacent to said corner posts, ladder members secured to said posts, the upper ones of said ladder members being adjacent to the top edge of car and in substantially same vertical planes as 60 other ladder members in same group, and top corner connection plates, said plates being provided with clearance recesses adjacent to top ladder members. 65
15. In a railway car, an underframe including longitudinal sills along the sides of the hopper opening and converging beyond the ends of the hopper opening, a truck including side frames pivoted intermediate their ends to the converging portions of 70 said sills, a hopper end wall extending downwardly below the plane of the tops of said side frame and adjacent to the inner ends of the latter but between the same and the middle of the car, said wall being 75 curved horizontally from each side adjacent to said side frames outwardly toward the end of the car, said side frames being pivoted intermediate their ends to said sills so that the inner ends of said side frames move 80 away from the middle of the car when said side frames swing on their pivots, the radius of the side frame end movement being less than the radius of the hopper wall curvature. 85

In testimony whereof I hereunto affix my signature this 10th day of July, 1922.

WILLIAM M. SHEEHAN.
